SHIPPING AND COOLING CONTAINER

Edgar J. Sabath and Percy E. Finch, Chicago, Ill.

Application March 31, 1934, Serial No. 718,498

8 Claims. (Cl. 62—32)

This invention relates to a container and represents an improvement upon our co-pending application, Serial No. 708,319, for Shipping and cooling container. An object of the invention is 5 to provide a container equipped with efficient cooling means which is readily accessible, and which is removable from the container. A further object is to provide an improved container equipped with cooling means by which a beer keg 10 of the usual tapered construction may be employed. Other specific objects and advantages will appear as the specification proceeds. The invention is illustrated in a preferred embodiment, by the accompanying drawing, in which—

15 Figure 1 is a broken vertical sectional view of a container embodying our invention; and Fig. 2, a similar view of a modified form of container embodying our invention.

In the illustration given in Fig. 1, A designates 20 the cylindrical casing member; B, the head closing the open top of casing A; and C, the barrel or keg. The casing A, head B and barrel C are described in detail in our co-pending application mentioned above.

25 The casing A comprises an outer wall 10 and an inner spaced wall 11, said walls forming the sides and bottom of the container. The walls are preferably made of aluminum or some similar light metal or alloy. Near the top of the member A, we provide a circular insulation and bracing strip 12 which may be of wood or other suitable material. Above the strip 12 is secured a rubber sealing strip 13. Suitable insulation is employed between the inner and outer walls 11. 30 The details of such insulation are described in our co-pending application designated above.

The head B comprises an outer wall 14 and an inner wall 15. The two walls are connected at their lower ends by a circular strip 16 of wood or other suitable material, the strip 16 being adapted 40 to lie against the sealing strip 13 of the container A. The lower wall 15 is provided eccentrically with an opening through which extends a cylindrical outlet member or tube 17. The member 17 also extends through the top wall 14 and provides a frustro conical seat 18 receiving a sponge rubber plug 19. The bottom wall 15 is also provided with a semi-circular opening and a portion of the wall adjacent the opening is turned 45 downwardly at 20 to form a depending compartment. A lid 21 for the compartment is secured to the depending wall 20 by hinges 22 and by a spring-latch 23. The lid 21 is provided on its interior with an insulation plate 24 having spaced 50 perforations therein. A dry-ice receptacle with-

5 in the interior of head B is provided by the insulation walls 25 which may be formed of magnesite or other suitable material. It will be noted that the receptacle thus formed is provided with ledges extending to each side of the downwardly turned walls 20. By this means, cakes of dry-ice can be conveniently supported within the compartment and above the lid 21.

The top wall of head B is also preferably depressed to provide a semi-circular opening 26. 10 Preferably, the depressed portion of the wall is stepped at 27 to provide a ledge to support the drain plate 28. The side walls of head B are preferably provided with clamping devices 29, which are of well known construction, and which 15 are adapted to engage the bead of outer wall 10 of container A to lock the head to the container.

The barrel C may be formed of any suitable material such as wood, metal, etc. We prefer to 20 form it of tin-lined steel. The barrel may be formed in the usual shape, having inwardly tapering upper and lower end portions 30, and provided with the usual spaced supporting rings 31. It will be noted that the inwardly tapering upper 25 end of the barrel C provides between it and the adjacent walls of container A, a space 32 which is roughly in the shape of the letter V.

In the illustration given, the upper end of the keg C is depressed as indicated at 33. Within 30 one-half of the depression, there is secured a platform member 34 which fills out that portion of the cask head even with the top of the edge wall. The lower depressed platform 34 is preferably cut away at 35 to form a substantially circular opening adapted to receive a barrel fitting 36 provided by a depressed portion of the platform 34. The fitting 36 is provided with a cupped body portion which is centrally provided with an upwardly extending and externally threaded neck 37. 35

Extending into the barrel C through neck 37 is a draught pipe 38 which extends also through the tube 17 and plug 19 to a faucet and pump (not shown) of well known construction. A fitting 39 extends about pipe 38 and is provided with an 40 enlarged and internally threaded end 40 engaging neck 38. Within the recess 32 provided between the upper walls of barrel C and container A, and above the ring 31 of barrel C, we provide a dry-ice receptacle 41. It will be noted that the receptacle is shaped so as to substantially fill the recess 45 32 and to be supported therein by ring 31 or by the walls of barrel C and container A. The receptacle 41 comprises an annular vessel having an outer metal wall 42 and an inner insulation wall 50 55

43. A closure ring 44 formed of metal or insulation material is employed at the top of the receptacle 41 and is preferably perforated.

In the operation of the device, upon the removal of head B, dry-ice may be placed within the receptacle 41 and the closure 44 placed in position. Also, dry-ice may be placed within a compartment within head B. The beverage is drawn through pipe 38 and the faucet thereabove into the vessel supported on platform 28. When the container is shipped, the pipe fittings may be removed and the neck 37 stoppered. Also, a stopper may be employed for the conical neck 18.

In the modified form of construction shown in Fig. 2, the barrel C and container A are identical with that shown in Fig. 1. Instead, however, of employing the special type of head shown in Fig. 1, we employ a head D of simple construction. The head D is provided with an upper wall 45 and a lower wall 46, the two walls being connected by an annular ring 47 of wood or other suitable material. The walls are apertured at an eccentric point to receive a tube 48 providing at its upper end a conical seat 49. A sponge rubber plug 50 is received within seat 49. The upper wall 45 of head D is depressed to form a drain pan 51 and a perforated tray 52 is supported above the pan.

Fiber insulation or any other suitable insulation may be employed between the walls 46 and 45 of head D and also between the walls 14 and 15 of head B.

With the simple form of insulated head shown in Fig. 2, the dry-ice is supported only within the receptacle 41 which is the same as that shown in Fig. 2. With this construction, the dry-ice compartment within the head is omitted. When the head D is removed, the receptacle 41 may be lifted out of the container and filled or, if desired, it may be left within the recess 32 and charged with dry-ice while within the container.

While in the illustration given, we have shown a specific form of container and dry-ice receptacle, it will be understood that considerable changes in shape and form can be made without departing from our invention. The foregoing detailed description has been given for clearness of understanding only, and no unnecessary limitations should be understood therefrom, but the appended claims should be construed as broadly as permissible, in view of the prior art.

We claim:

1. In combination with a cylindrical container closed at its lower end, a barrel within said container having an inwardly tapering upper end providing between it and said container an annular recess, a receptacle for dry-ice adapted to be supported within said recess, and a removable closure for the upper end of said cylindrical container.

2. In combination, a cylindrical container having a closed lower end, a barrel within said container having an inwardly tapering upper end

providing between it and the wall of the container a V-shaped recess, an annular V-shaped receptacle for dry-ice adapted to be supported within said recess, a perforated closure for said receptacle, and a removable head for closing the upper end of said cylindrical container. 5

3. In combination, a container open at its upper end, an insulation head closing said container, a barrel within said container and providing between its upper ends and the container a recess, 10 a dry-ice receptacle supported within said recess, and a perforated closure for said receptacle.

4. In apparatus for the character set forth, a container open at its upper end, a head closing said upper end of the container, a barrel carried within said container and having an inwardly tapering upper end providing between it and said container a recess, a ring-support secured to said barrel, and a dry-ice receptacle within said recess and carried by said ring-support. 15

5. In combination, a cylindrical container having an open upper end, a removable head closing said upper end of the container, a barrel having an inwardly tapering upper end providing a V-recess between it and the wall of the container, 25 an annular V-shaped container for dry-ice adapted to lie within said recess and provided interiorly with insulation, and a perforated closure for said V-shaped container. 20

6. In combination, a cylindrical container having an open upper end, an insulated head closing the upper end of the container, a barrel within said container having an inwardly tapering upper end providing a recess between it and the wall of the container, and an arcuate dry-ice container received within said recess and supported therein 35 adjacent said barrel, said head being provided with a pipe opening therethrough. 30

7. In combination, a container open at its upper end, a head closing the upper end of said container and providing a dry-ice compartment therein, a barrel within said container and having its top wall extending below the dry-ice compartment within said head, said barrel providing between its upper end and said container a recess, and a dry-ice receptacle supported within said recess 40 about the upper end of said barrel. 45

8. In combination, a container open at its upper end, a head closing the upper end of said container and providing a dry-ice compartment therein, a barrel within said container and having its top wall extending below the dry-ice compartment within said head, said barrel providing between its upper end and said container a recess, and a dry-ice receptacle supported within said recess 50 about the upper end of said barrel, said head being provided with an opening therethrough and said barrel having its top wall provided with an opening aligned with the opening in said head. 55
